(57) **CLAIM**

The ornamental design for a screwdriver handle, as shown and described.

DESCRIPTION

FIG. 1 depicts a perspective view of a screwdriver handle showing our new design.

FIG. 2 depicts a top view of the screwdriver handle. The bottom view is identical to the top view.

FIG. 3 depicts a left side view of the screwdriver handle, i.e., rotated axially 90° counterclockwise relative to the view in FIG. 2.

FIG. 4 depicts a bottom view of the screwdriver handle, i.e., rotated axially 180° relative to the view in FIG. 2.

FIG. 5 depicts a right side view of the screwdriver handle, i.e., rotated axially 90° clockwise relative to the view in FIG. 2.

FIG. 6 depicts a front view of the screwdriver handle; and, FIG. 7 depicts a rear view of the screwdriver handle.
